UNITED STATES PATENT OFFICE.

JOHN G. HOOVER, OF WILKES-BARRE, PENNSYLVANIA.

TYPE-CASTING DEVICE AND MATRIX THEREFOR.

Application filed April 10, 1924. Serial No. 705,613.

To all whom it may concern:

Be it known that I, JOHN G. HOOVER, a citizen of the United States, residing at Wilkes-Barre, in the county of Luzerne and State of Pennsylvania, have invented certain new and useful Improvements in Type-Casting Devices and Matrices Therefor, of which the following is a specification.

The present invention relates to improvements in type casting arrangements.

More particularly the invention relates to improvements in type casting boxes, type setting sticks, and matrices which coact in a new and improved manner.

In typograph machines, such as disclosed in United States Patent Number 1,276,268 to Ludlow and similar machines, it is the practice to use matrices carrying only one face of type. For each kind of type, such as light, italic, or bold characters, a separate matrix is utilized. This results in the necessity for carrying and storing a great many matrices.

An object of the invention is to provide special devices whereby the number of matrices and storage space therefor may be considerably reduced.

A further object of the invention is to provide an arrangement, where the characters set up in the stick may be inserted in the box in a manner to print in any one of three styles of type.

Other objects of the invention are such as may be attained by a utilization of the devices and principles hereinafter set forth and claimed:

Referring to the drawings—

Fig. 1 is a bottom view of the improved stick.

Fig. 2 is the top view of the improved stick.

Fig. 3 is a sectional view taken along line A A of Fig. 1.

Fig. 4 is an end view of the stick.

Fig. 5 is a side view of the special shape of matrix used.

Figs. 6, 7 and 8 are views showing the various type faces of the matrix.

Fig. 9 is a side elevation showing the casting box with the set up stick partially inserted therein.

Fig. 10 is a plan view of the casting box partially in section.

Fig. 11 is a bottom view of the casting box with matrices shown in casting position.

Fig. 12 is an end view of the casting box with the stick shown in section.

The type setting stick comprises end pieces 1 and 2, connected by bars 3 and 4. Bars 60 3 and 4 have inner guide surfaces 5 and 6 formed thereon in a manner to permit the matrices to nest in the stick. A block 7 is shaped and arranged to slide in the stick, as shown in Figs. 1, 2 and 3, and is adapted 65 to be forced to the right in Figs. 1 and 2 by a tightening screw 8 extending through a suitably threaded hole in end piece 1, and having a knurled head 10. In the center of the four sides of ends pieces 1 and 2, slots 70 11 are formed. In block 7 a similar slot 12 is formed in the center of the upper edge thereof, and in the center of the other three edges shallow slots 13 are formed. As shown in Fig. 3, the bottom and sides of slots 75 12 and 13 align with the bottoms, and sides of slots 11 when the block 7 is in operating position.

Each matrix comprises a metallic piece shaped to fit into the stick in such manner 80 that surfaces 15 will nest into surfaces 5 of the stick and surfaces 16 will nest into surfaces 6, as shown in Fig. 12. In the upper edge of each matrix a relatively deep slot 17 is formed, and in the other three 85 edges, shallow notches 18, 19 and 20 are formed. When the matrices are set into position and clamped in the stick the bottoms and sides of slots 17 will align with the bottoms and sides of slots 11 and 12, 90 and the bottoms and sides of slots 18, 19 and 20 will align with the bottoms and sides of slots 11 and 13 in the respective sides of the end pieces 1 and 2, and in the block 7. In slots 18, 19 and 20 of the matrices, different styles of the same letter are cut, as 95 shown in Figs. 6, 7 and 8. Preferably, a bold, light, and italic form of each character is applied as shown, so that when matter is set up in the stick it will appear on one side 100 of the stick in light type, and on another side of the stick in italic type, and on a third side of the stick in bold type. All matter is therefore set up each time in the three styles of type, and any style may be 105 chosen to be cast. It will be understood that the type is set up in the stick by setting the matrices in proper position and the matrices are then clamped in position by tightening the screw 9 to force block 7 to 110 the right in Fig. 1.

A special casting box to receive the stick

- and matrices is provided. This comprises a base plate 21 suitably formed to be secured to a casting machine, and provided with an opening 22 in the base thereof through which the molten metal flows upward. Immediately over opening 22 a box structure 23 is formed integrally with the base. Extending through 23 is an opening 24 into which tongues 25, 26 and 27 extend. 10 Opening 24 extends slightly below the upper surface of base plate 1, and shallow grooves 28 extend from the ends of the box 23 forming a guide groove to permit insertion of the stick and matrices in the box for casting. The interior of the box is so shaped and of such size that the set stick will fit snugly therein, with tongues 25, 26 and 27 respectively fitting into three of the slots 11 in the end pieces 1 and 2 of the stick, in aligned slots 17 of the matrices, and in two of the aligned shallow slots 18, 19 and 20 of the matrices, so that the stick may be inserted with either the bold, light or italic type above opening 22 in position 20 to be cast. As shown in Fig. 12, the stick is set for casting a line of light type. 15 It will be clear that by simply turning over the stick, any one of the three styles of type may be set for casting, and that in each casting position, the matrices will be held in alignment by the three tongues 26, 25 and 27, fitting into aligned slots 17, 18 and 20, 17, 19 and 20, or 17, 18 and 19 of the matrices. 25 Having described a preferred embodiment of my invention what is desired to be secured by Letters Patent and claimed as new is:
1. In combination, a type setting stick 30 comprising a plurality of guide slots, a plurality of matrices each having a plurality
- of type carrying faces and adapted to fit into said stick in one position only with relation to said stick; a slot formed in a non-type carrying face of each matrix and so arranged that when the matrices are positioned in said stick said slots will be aligned with one of the guide slots in said stick; and a casting box comprising an opening into which a plurality of guide tongues project and into which said stick carrying said matrices is adapted to fit in such manner that any one of said guide tongues will fit into the aligned slots in said stick and said matrices and will maintain said matrices in any one of a plurality of casting positions. 45
2. The combination as set forth in claim 1, together with a guide slot in each remaining type carrying face of said matrices, arranged to align with the remaining guide slots in said stick in such manner that a plurality of the guide tongues in said casting box will fit into a plurality of the aligned slots in said stick and matrices and maintain said matrices and said stick securely in any one of a plurality of casting positions. 50
3. In combination, a type setting stick comprising a plurality of casting faces; and a plurality of matrices adapted to fit into said stick in only one position with relation thereto, each matrix comprising a plurality of type faces upon each of which the same character in different style is carried in such manner that when said matrices are set in said stick, the same matter will be set up on each casting face of said stick, but will appear in different styles of type on each face. 55
- In testimony whereof, I affix my signature. 60

JOHN G. HOOPER.
